UNITED STATES PATENT OFFICE.

ERNEST F. LOEWER, OF GOODWIN, ARKANSAS.

COVER FASTENER.

Application filed April 23, 1925. Serial No. 25,422.

This invention relates to improvements in fastening means particularly adapted for use in connection with covers for oil barrels, storage tanks and the like.

5 An important object of the invention is to provide a cover fastener which will prevent the unauthorized removal of covers from gasoline storage tanks, barrels and the like.

10 A further object of the invention resides in the provision of a fastening device of this character which may be readily mounted on the cover and locked in position without great effort.

15 A still further object of the invention is the provision of a cover fastener of the above character which is simple yet durable of construction and efficient for the purpose intended.

20 Other objects and advantages of this invention will become apparent as the description progresses.

25 In the accompanying drawings forming a part of this specification and in which like numerals are employed to designate corresponding parts throughout the same:

Figure 1 is a side elevation of my improved device shown operatively associated with a tank,

30 Figure 2 is a top plane view of the same, Figure 3 is a side elevation of the device showing the tank and cover members in section,

35 Figure 4 is a transverse sectional view taken on the line 4-4 of Figure 1,

Figure 5 is a perspective view of one of the fastening members,

40 Figure 6 is a perspective view of the container cover and fastening member, and

Figure 7 is a side elevation of a common 45 form of oil barrel showing my device mounted in association therewith.

In the drawings, wherein for the purpose of illustration is shown the preferred embodiment of my invention, the numeral 10 generally indicates a conventional type of storage tank such as is usually employed for the storage of gasoline or the like. It is customary to provide a tank of this character with an outlet sleeve as shown at 11, this sleeve being usually internally screw threaded for the purpose of receiving a suitable cover. Most of these covers are constructed with cylindrical bodies as at 12 provided with an over-hanging cap at the upper extremity as shown at 13, this cap being preferably provided with hexagonal

sides to permit the application of a wrench. The body 12 is externally screw threaded for engagement with the threads formed on the sleeve 11.

60 The cover is fastened securely in association with the storage tank and locked against displacement by means of a pair of crank rods 14 composed of longitudinal handles 15 provided on one extremity with a reduced extension having a longitudinal slot to provide an ear 16. The opposite extremities of these rods are provided with angular extensions 17 externally screw threaded at their ends as at 18. One of the crank rods 70 14 is adapted to engage a screw threaded bore formed in the upper portion of the cover 12 while the other crank rod engages a similar bore formed in a suitable lug 19 formed integral with the upper portion of 75 the tank. It is to be noted that the reduced extensions or ears 16 are formed on the adjacent ends of the crank rods in order that the same may engage to form aligned locking means as clearly shown in Figures 3 and 80 4. When it is desirable to lock the cover the ears are placed in parallel position, the slots being in alignment for the reception of the bail of a suitable type of lock preventing movement of the crank rods.

85 With reference to Figure 7, the numeral 10 generally designates a conventional type of barrel usually of metallic construction employed in the delivery of fuel and oil to dispensing stations. In this type of container the lug 19 is formed on the top plate and the device as previously described suitably mounted thereon.

90 In use, the device may be readily locked against unauthorized removal of the contents or mixture thereof. When it is desired to remove the cover for filling or for any other purpose the crank rod mounted in the cylindrical lug 19 is moved to a position substantially transverse to the longitudinal 100 axis of the tank whereas the opposite crank rod may be readily rotated for the removal of the cover. It is apparent that the device provides compact and durable means for locking covers of this character, especially 105 intended for use in connection with oil barrels and gasoline storage tanks, preventing unauthorized removal of the contents or the addition of foreign matter thereto.

110 It is to be understood that the form of my invention herewith shown and described is to be taken as the preferred example of

the same and that various changes as to the shape, size and arrangement of parts may be resorted to without departing from the spirit of the invention, or the scope of the 5 subjoined claims.

Having thus described my invention, I claim:

1. In combination with a cover provided with an internally screw threaded bore, and a lug mounted adjacent the cover provided with a similar screw threaded bore, of a pair of angular rods screw threaded on the remote extremities for engaging the recesses formed in the cover and lug, and ears formed 15 on the adjacent extremities for connection of locking means.
2. In combination with a cover having an internally screw threaded recess, a lug mounted adjacent the cover provided with a similar screw threaded recess, of a pair of operating rods threadedly mounted in the recesses in the cover and lug, and ears formed 20 on the adjacent extremities of the rods adapted to meet in alignment for the reception of a lock.
3. In combination with a storage tank, a cover threadedly engageable with the said tank, and a lug formed on the tank, of closure means including a pair of angular rods 25 screw threaded on the remote extremities for engaging suitable recesses formed in the cover and lug, and slotted extensions formed on the adjacent ends of the rods adapted to coincide in the closed position and engage a suitable lock.
4. In combination with a barrel, a cover threadedly mounted in the said barrel, and a lug formed on the barrel, of closure means 30 including a pair of rods having angular extensions, the extreme ends of the extensions being screw threaded for engagement with

suitable recesses formed in the cover and lug, and a pair of slotted ears formed in the adjacent ends of the rods adapted to engage in parallel alignment and receive 45 therein the bail of a lock.

5. In combination with a barrel, a cover threadedly mounted in the upper portion of the barrel, and a lug formed on the barrel, of closure means including a pair of rods comprising longitudinal handle portions, angular extensions formed on one of the handle portions, the extreme ends of the extensions being screw threaded to engage screw threaded bores formed in the cover and lug 50 member, and slotted ears formed on the opposite extremities of the handle portions adapted to engage in parallel alignment for the reception of suitable locking means.

6. In combination with a receptacle having 55 a detachable cover, fastening means including a member detachably connected with the cover, a complementary member attached to the receptacle and arranged for swinging movement thereon, the inner ends of the 60 said members being arranged for overlapping engagement and provided with aligned openings to receive therein a locking device.

7. In combination with a receptacle having 65 an opening therein and a cover adapted 70 for threadedly enclosing the said opening; fastening means including an angular member threadedly engaged with the said cover, a complementary angular member threadedly secured upon the receptacle adjacent 75 the said cover, the adjacent ends of the angular members being arranged for overlapping parallel contacting arrangement and having slots formed therein for engagement of the locking device.

In testimony whereof I affix my signature.
ERNEST F. LOEWER.
